UNITED STATES PATENT OFFICE.

EDWARD B. VANDERGAW, OF BROOKLYN, AND JULES HEINRICH, OF NEW YORK,
N. Y., ASSIGNEES TO FRED BUTTERFIELD & CO. INC., OF NEW YORK, N. Y., A COR-PORATION OF NEW YORK.

DESIGN FOR FLOCKED VOILE FABRIC.

Application filed September 18, 1923. Serial No. 7,244. Term of patent 3½ years.

To all whom it may concern:

Be it known that we, EDWARD B. VANDERGAW and JULES HEINRICH, citizens of the United States, residing, respectively, in the borough of Brooklyn and the borough of Manhattan, in the city and State of New York, have jointly invented a new, original, and ornamental Design for Flocked Voile Fabric, of which the following is specification, reference being had to the accompanying drawing, forming part thereof.

The figure is a plan view of a piece of flocke^d voile fabric showing our new design.

We claim:

The ornamental design for flocke^d voile fabric, as shown.

EDWARD B. VANDERGAW.
JULES HEINRICH.
